COMBINED BRUSH AND SQUEEGEE

James H. Carter, Oakland, Calif.

Application October 9, 1951, Serial No. 16,884

Term of patent 14 years

(Cl. D9—2)

To all whom it may concern:

Be it known that I, James H. Carter, a citizen of the United States, residing in Oakland, county of Alameda, State of California, have invented a new, original, and ornamental Design for a Combined Brush and Squeegee, of which the following is a specification, reference being had to the accompanying drawings, forming part thereof, in which:

Figure 1 is a top plan view of a combined brush and squeegee, showing my new design;

Figure 2 is a side elevation thereof. Both sides are identical; and

Figure 3 is a front end elevational view of the combined brush and squeegee.

The essential features of the design are shown by full lines in the drawing.

I claim:

The ornamental design for a combined brush and squeegee, substantially as shown and described.

JAMES H. CARTER.
